Inventor,

UNITED STATES PATENT OFFICE.

CHRISTOPHER COLUMBUS OLSON, OF FOUTS, OKLAHOMA TERRITORY.

STAY-WIRE-APPLYING DEVICE.

SPECIFICATION forming part of Letters Patent No. 633,894, dated September 26, 1899.

Application filed July 10, 1899. Serial No. 723,363. (No model.)

To all whom it may concern:

Be it known that I, CHRISTOPHER COLUMBUS OLSON, a citizen of the United States, residing at Fouts, in the county of Lincoln and 5 Territory of Oklahoma, have invented a new and useful Fence-Machine, of which the following is a specification.

This invention relates to fence-machines or implements of that character employed to apply stay-wires or what are sometimes termed "mesh" wires to runners or stringers after the latter have been arranged in parallel relation or fixedly held by suitable supports.

The object in view is to provide means for 15 effectively securing stay-wires or the like in a fixed position on the stringers or runners, and to utilize for such purpose a device that is particularly intended to be readily transported from one place to another and completely embodying all the mechanism necessary to effect the conjunctive assemblage of 20 said stay-wires and stringers or runners.

The invention consists, essentially, of a 25 portable support having a series of twisting-heads arranged in vertical alinement thereon and comprising oppositely-positioned diverging arms with seat-grooves between them and inner and outer engaging projections reversely disposed, the said heads being actuated by the shifting movement of an operating-bar.

The invention further consists of a portable 35 support having a series of twisting-heads thereon arranged for simultaneous rotation and adapted to act directly on the stringers or runners intermediate upper and lower similar border devices, the said upper and lower border stringers or runners being threaded through tubular twisters connected 40 to the operating devices and having diagonally cut-off ends with openings through the longer portions thereof to receive the upper and lower ends of the stay-wires and operable to twist the ends of the stay-wires around 45 the upper and lower border stringers or runners.

The invention further consists in the details of construction and arrangement of the several parts, which will be more fully hereinafter described and claimed.

In the accompanying drawings, Figure 1 is 50 a front elevation of a machine or implement embodying the invention and shown applied

to stringers or runners, the several parts being in a position just previous to the final securing of a stay-wire, shown in position in relation thereto. Fig. 2 is a front elevation of one of the twisting-heads and a part of the support and operating-bar, showing the first position, or as the said twisting-heads appear when applied to the runners. Fig. 3 is a view similar to Fig. 2, showing the second position of the parts and the stringer or runner as partially twisted. Fig. 4 is an elevation embodying the features shown by Figs. 2 and 3 and illustrating the twisting-head as just completing its operation and previous to its withdrawal from the stringer or runner and the fastening of the latter over the stay-wire. Fig. 5 is a transverse vertical section showing parts in elevation of one of the twisting-heads and the support-operating bar and connection between the latter and the shank of the said head. Fig. 6 is a detail perspective view of one of the twisting devices for fastening the upper or lower end of the stay-wire with the upper or lower border runner or stringer. Fig. 7 is a detail view showing the runner or stringer connected to the stay-wire. Fig. 8 is a detail perspective view of one of 80 the twisting-heads.

Similar numerals of reference are employed to indicate corresponding parts in the several views.

The numeral 1 designates a main support 85 which is portable and preferably in the form of an elongated bar having an upper angularly-disposed grip or handle 2. The support 1 can be readily moved from one position to another, and has rotatably secured thereto a 90 series of twisting-heads 3, having hubs 4, mounted in openings in the said support and provided with rearwardly-projecting angular or polygonal shanks 5. Each shank 5 is firmly fixed to one end of a link 6, the opposite ends of said links being pivotally attached to an operating-bar 7, the said links 6 having movement in parallel relation, and secured to the upper end of said bar 7 is a grip or handle 8, by which said bar is actuated. 100 When the bar 7 is moved, the links 6 are uniformly and simultaneously shifted and the twisting-heads 3 are accordingly rotated equally.

Each twisting-head has opposite pairs of 105 diverging arms 9 and 10 secured thereto, and

between the inner edges of one of each pair of said arms a seat-groove 11 is constructed in said head, and the opposite walls thereof in part are continuous with or merge into the adjacent inner edges of diagonally-opposite arms 9 and 10. The seat-groove 11 is deep enough to completely receive a stay-wire, and the arrangement of the heads on the support is such that the said seat-grooves 10 will be in vertical alinement at the time necessary to insert the stay-wire and after a twist, hereinafter referred to, of suitable form has been made in the several runners or stringers intermediate of the upper and lower 15 border runners or stringers.

The opposite pairs of arms 9 and 10 are divergent and varied to some extent in features of construction. One of each pair of arms 9 and 10 has an outer holding projection 12, 20 the said projections on the opposite arms being diagonally disposed relative to the outer or face side of said arms. The inner edges of the remaining arms of the pairs 9 and 10 are formed with outturned lips 13, which 25 provide guides to permit the runners or stringers to move under a part of the arms, in a manner which will be hereinafter specified.

On opposite sides of the seat-groove 11, in each head 3, twisting projections 14 are located and stand outward and are diagonally arranged relative to the line of the said seat-groove. The projections 14 are nearer the arms carrying the projections 12 and both projections 12 and 14 have such an angle afforded them by definite prearrangement and calculation as to keep and hold the wire runners or stringers during the operation of forming the twists.

On one edge of the support 1, at the upper 40 and lower portions thereof, sprocket-wheels 15 are rotatably mounted in suitable hangers or bearings and have tubular twisting-hubs 16. The inner ends of the said hubs 16 are cut off in a plane oblique to the axial line of the 45 said hubs, as at 17, and where the longer or projected portion of the hub is formed by this means an opening or eye 18 is bored or otherwise constructed. The said upper and lower tubular twisting-hubs 16 are primarily arranged so that the inner beveled ends of the 50 same will stand in reverse position or so that the longest portions containing the openings or eyes 18 will be respectively above and below the upper and lower border stringers or runners. The sprocket-wheels 15 are intended to be operated by suitable means, and preferably through the engagement therewith of a chain belt, as shown by dotted lines, and which will be actuated by an intermediate 55 driving device, also illustrated by similar lines. The said sprockets will be rotated in a direction to cause the hubs thereof to perform their requisite function in an effective manner or so that the ends of the stay-wires 60 may be wound on the upper and lower border-wires in neat and durable condition.

In operation the improved device or imple-

ment is brought up into engaging relation with a plurality of runners or stringers, which are indicated by 19 in the drawings. The 70 heads 3 are positioned, as shown by Fig. 2, and when so arranged the operating-bar 7 will be at its highest point of movement. The runners or stringers 19 are interlaced through or between the projections 12 and 14 throughout the whole series of heads, and the upper and lower border runners or stringers will be threaded through the tubular twisting-hubs 75 of the sprocket-wheels 15.

By reference to Fig. 2 it will be observed 80 that the deflections of the projections 12 and 14 are such that they will practically extend over the runners or stringers, and all of the twisting-heads after this arrangement has been attained will be simultaneously rotated 85 in the direction of the arrow by pressing downwardly on the grip or handle 8 and which causes the operating-bar 7 to be shifted outwardly from the support 1, as shown by Fig. 3. The runners or stringers will now be held 90 in bent condition by the diagonally opposite projections 14 and the heads 3, which will turn or rotate about an eighth of a revolution. The downward pressure on the grip or handle 8 is continued until the operating-bar 7 95 reaches the position shown by Figs. 1 and 4, and the heads will have then been rotated a quarter of a revolution, and the twist or bend of each runner or stringer will stand in a diagonal plane to the vertical opposite 100 that illustrated by Fig. 3. The lips 13 on the diagonally opposite arms 9 and 10 of each pair of arms permit the arms carrying them to ride over the runners or stringers and guide the latter under a portion of the said 105 arms or those carrying the said lips. This position of the runners or stringers clears the groove-seats 11 by forcing a part of the said runners or stringers back of the opposite terminations of said groove-seats and forming the diagonal bends of the runners or stringers which lie across about the central portion of the said seats, and thus provide receptive loops. The stay or mesh wires 20 now are inserted through the loops formed in 110 the runners or stringers and rest in the seats 11, the upper and lower ends of the said stay or mesh wires being threaded through the openings 18 in the tubular twisting-hubs of the sprocket-wheels 15. These sprocket-wheels up to this time have been inoperative, 115 but are now rotated to fasten or wind the ends of the stay or mesh wires around the upper and lower border runners or stringers. After the stay or mesh wires are thus secured 120 at their opposite ends the twisting-heads 3 are slightly loosened by a reverse or upward movement of the operating-bar 7 and through the medium of the links 6 will permit the projections 14 to be disconnected from the runners or stringers, and immediately after this 125 dissemblage takes place the runners or stringers will spring back and interlock with the stay-wires in the manner shown by Fig. 7.

The return or back spring movement of the runners or stringers when released from the projections 14, as just explained, will be due to the tension on said runners or stringers, which may be exerted or applied by any suitable means. In the application of the said wires it is necessary that they go behind the bottom runner and in front of the top runner, or vice versa, in order to attain the desired result. It will also be observed that the projections on the twisting-heads are deflected, so as to receive a runner or stringer without bending the same. It will also be understood that the present device or implement can be used in the field in setting up fences or its features of construction embodied in a fence-weaving machine having suitable reels and a winding-drum. This application will not affect the operation of the parts as described, as they will remain the same and without variation in the least particular.

When the device or implement is first brought up to the runners or stringers, the operating-bar 7 must also be first arranged at its highest adjustment and so that the links 6 will extend at reverse angles to the position shown in dotted lines by Fig. 1. The grip or handle 2 is utilized to hold the support 1 in steady upright position and the projections 12 assist in sustaining the engagement of the twisting-heads with the said runners or stringers until a rotation of said heads ensues and the projections 14 exert a hold-fast bite on the said runners or stringers. If there should be too much slack in the twist of the runners or stringers after the twisting-heads are disengaged therefrom, this defect can be quickly regulated or cured by increasing the tension on the said runners or stringers.

The beveled or oblique ends of the tubular twisting-hubs of the sprocket-wheels 15 permit a clearance of the stay-wires and also a feed of the terminals of the said threaded wire through the openings 18 in regular order around the upper and lower border runners or stringers. The said twisting binding of the terminals of the stay-wires will continue until freedom or liberation of the terminals from the tubular hubs takes place and owing to the coils formed, which gradually draw inward on such terminals.

The number of twisting-heads may be increased or decreased to compensate for the number of runners or stringers, and in some instances only a portion of the said twisting-heads will be used, as will be obviously apparent in fences embodying a comparatively small number of runners or stringers or those having said latter devices spaced apart at greater intervals.

Changes in the proportions, size, and minor details of construction might be resorted to without departing from the nature or spirit of the invention or sacrificing any of the advantages thereof.

Having thus described the invention, what is claimed as new is—

1. A device for attaching stay-wires to wire fences, comprising a support, a plurality of twisting-heads thereon having groove-seats therein and projections for holding the runners or stringers of the fence in position over and across opposite portions of the said groove-seats, and means for operating said heads.

2. A device for attaching stay-wires to wire fences, comprising a support, a plurality of twisting-heads rotatably mounted therein and having groove-seats between opposite pairs of diverging arms and outstanding projections, the said grooves being adapted to receive the stay-wires and the projections and arms serving to hold the runners or stringers of the fence in looped condition over and adjacent opposite portions of the groove-seats to receive the stay-wires, and means for operating said twisting-heads.

3. A device for attaching stay-wires to fences, having twisting devices for securing the upper and lower terminals of the stay-wire, and consisting of sprocket-wheels having tubular hubs with the inner ends beveled and formed with eyes through the longer portions, the said inner beveled ends of the hubs being primarily arranged in reverse position, and means for operating the said sprocket-wheels.

4. A twisting-head for implements for attaching stay-wires, comprising opposite pairs of diverging arms having a groove-seat between them, and inner diagonally-disposed twisting projections adjacent opposite ends of said seats and in reverse position, the outer portions of one of each pair of arms in diagonal relation having holding projections thereon and the inner edges of the remaining arms formed with outstanding lips.

5. A device for attaching stay-wires to wire fences, comprising a support, a plurality of twisting-heads mounted thereon for simultaneous rotation and having groove-seats, and the upper and lower independently-movable twisting devices having tubular portions with eyes therein adapted to align with the seats in the said heads.

6. A twisting-head for a device for attaching stay-wires to wire fences, comprising opposite pairs of diverging arms, one arm of each pair in diagonal relation with the other having outstanding holding projections thereon, and the central part of the twister having outstanding twisting projections in diagonal relation, all of said projections being deflected, so as to receive a runner or stringer without bending the same.

In testimony that I claim the foregoing as my own I have hereto affixed my signature in the presence of two witnesses.

CHRISTOPHER COLUMBUS OLSON.
